CLAIM

The ornamental design for a building structure for a carwash, as shown and described.

DESCRIPTION

FIG. 1 is a left side elevation view of a building structure for a carwash showing my new design.

FIG. 2 is a right side elevation view thereof, generally showing the inside of the building structure as viewed from the right side.

FIG. 3 is a top plan view thereof.

FIG. 4 is a front elevation view thereof; and,

FIG. 5 is a rear elevation view thereof.
